UNITED STATES PATENT OFFICE.

MARTIN LINDBLAD, OF COGSWELL, NORTH DAKOTA.

TRANSPORTATION APPARATUS.

SPECIFICATION forming part of Letters Patent No. 792,997, dated June 20, 1905.

Application filed March 20, 1905. Serial No. 251,093.

To all whom it may concern:

Be it known that I, MARTIN LINDBLAD, a subject of the King of Sweden and Norway, residing at Cogswell, in the county of Sargent 5 and State of North Dakota, have invented certain new and useful Improvements in Transportation Apparatus; and I do declare the following to be a full, clear, and exact description of the invention, such as will enable others 10 skilled in the art to which it appertains to make and use the same.

My invention relates to improvements in transportation apparatus, and more particularly to a sled or the like which is self-propelled by means of an apparatus which it carries and which engages and runs upon a cable or the like stretched over snow or ice and extending in the direction to be traveled by the sled.

The object of the invention is to provide a simple and efficient sled-railway for use in cold climates by means of which traffic or transportation will be greatly facilitated.

With the above and other objects in view 25 the invention consists of certain novel features of construction, combination, and arrangement of parts, as will be hereinafter described and claimed.

In the accompanying drawings, Figure 1 is 30 a top plan view of an apparatus constructed in accordance with my invention. Fig. 2 is a vertical longitudinal sectional view through the same, and Fig. 3 is a vertical transverse sectional view.

In the embodiment of my invention illustrated in the drawings, the numeral 1 denotes 35 a sled comprising a frame 2, having runners 3, which are adapted to slide upon snow or ice. The sled may be of any desired form and construction and is adapted to be propelled in 40 either direction by means of a mechanism 4, which is mounted upon the sled-frame 2 and which is adapted to engage and run upon a steel-wire cable or other flexible element 5, 45 which is stretched loosely over the snow or ice between the points or places between which it is desired to have the sled travel.

The apparatus or mechanism 4 for gripping and drawing upon the cable 5 for the purpose

of propelling the machine comprises two gripping-wheels 6 and 7, which are secured upon the lower portions of vertically-extending shafts 8. These shafts 8 have their upper ends connected by universal joints 9 to the lower ends of vertical shafts 10, which are mounted 55 in bearings 11 upon cross-beams 12 of the frame 2. By mounting the gripping-wheel 6 in this manner upon the swinging shafts 8 they may be moved toward and from each other to tightly grip the cable 5, which passes 60 between them, and in order to hold them in such engagement I provide the lower ends of the shafts 8 with spring-pressed bearings 14. These bearings or bearing-blocks are slidably mounted in slots 15, formed in brackets or 65 supports 16, provided upon the frame 2 of the sled, and they are forced inwardly toward each other by coil-springs 17, which are confined in the slots 15 in the brackets 16 between said bearings 14 and the outer ends of 70 said slots. The wheels 6 and 7 have their lower ends tapered slightly, as shown at 18.

Any desired means may be provided for 75 rotating the gripping-wheels 6 and 7 in either direction, so that the sled may be propelled in either direction along the cable 5. As shown, each of the shafts 12 has upon its upper end a gear 13, which may be driven by a suitable mechanism. The sled may be propelled by steam, electricity, or any other 80 power, the motor (not shown) being mounted upon the frame 2.

In order to guide the cable 5, which passes 85 through suitable openings formed in the upwardly-curved ends of the sled between the gripping-wheels 6 and 7, I provide at the front and rear of the sled guide pulleys or wheels 25. The latter have grooved peripheries to receive the cable 5 and are journaled, as at 20, upon one side of vertical beams or uprights 27 in 90 the frame 2, as shown. This construction permits the cable to be readily applied to or removed from said guide-pulleys.

The construction, operation, and advantages of my invention will be readily understood from the foregoing description, taken 95 in connection with the accompanying drawings. It will be seen when the gripping-

wheels 6 and 7 are rotated they will run upon the cable 5 and move the sled in either direction, according to the direction of rotation of said wheels.

5 While I have shown and described my invention as applied to a sled, it will be understood that the same may be used upon a wheeled vehicle or a boat as well. It will be further understood that various changes in 10 the form, proportion, and the minor details of construction may be resorted to without departing from the principle or sacrificing any of the advantages of this invention.

Having thus described my invention, what 15 I claim as new, and desire to secure by Letters Patent, is—

1. An apparatus of the character described, the combination with a cable or the like, of a sled or other movable object, a pair of shafts, 20 gripping-wheels upon said shafts adapted to receive said cable between them, a second pair of shafts, universal joints or connections between said shafts, sliding spring-pressed bearings for the lower ends of the first pair of

shafts, and means for driving the second pair 25 of shafts, substantially as described.

2. In an apparatus of the character described, the combination with a cable or the like, of a sled or other movable object, a transverse beam in said sled, vertical shafts upon 30 said beam, swinging shafts having their upper ends connected by universal joints to said vertical shafts, gripping-wheels upon said swinging shafts, slotted guides, bearings for the lower ends of said swinging shafts slidably 35 mounted in the slots in said guides, springs in said guides to force said wheels into engagement with said cable, means for driving said vertical shafts and supporting-pulleys to guide said cable to and from said wheel, substantially as described.

In testimony whereof I have hereunto set my hand in presence of two subscribing witnesses.

MARTIN LINDBLAD.
